BURNER FOR VULCANIZING APPARATUS

Wilhelm Friedrich Peters, Frankfurt am Main
Niederursel, and Josef Riesinger, Frankfurt
am Main, Germany, assignors to Valex J. Del-
homme, Carenero, La.

Application April 18, 1950, Serial No. 156,664
In Germany February 9, 1949

3 Claims. (Cl. 126—43)

1

The invention relates to a portable vulcanizing apparatus of comparatively small size, which is suitable for transport in vehicles and enables the user of the vehicle to repair damage to the tires at any time on the journey by a reliable vulcanization.

It is known that the vulcanization of rubber must take place under heat and pressure at a determined medium operating temperature. Vulcanizing apparatus have been proposed which press the patch to be vulcanized between clamping surfaces and are fitted with a heating device. Usually, however, the upper clamping surface of the apparatus is heated and constitutes a container which is intended for the reception of liquid fuel. It is difficult in such apparatus with variations in outside temperature to keep the operating conditions suitable for vulcanization. Moreover, they involve a comparatively large consumption of fuel because the flame heat of the heating apparatus is not used, and are also inconvenient in use and to service.

The apparatus according to the invention removes these disadvantages. It consists of a heatable press with a horizontal clamping surface and is characterized in that the lower clamping surface is constituted by the top cover of a pot-like container for the reception of the heating device. In this case therefore, the lower clamping surface is hot. Preferably the heating is effected by means of a burner fitting into the pot-like container and which is operated by a cartridge of solid fuel, such for example as resin, spirit, or the like. Such fuel cartridges develop a medium heat, particularly suitable for the operation of vulcanizing apparatus, and can be adjusted not only to the size and thermal requirements of the apparatus to be heated, but can if need be adjusted in depth in the burner so that it is possible to regulate the heating without use of control apparatus in such a way that a constant operating temperature is achieved, despite changes in external temperature.

The heated lower clamping surface can be removed from this container in order to achieve quick cooling of the apparatus. It is conveniently depressed from the edge towards the center, so that the parts to be vulcanized come under higher pressure at the edge and run out thin. The upper clamping surface is preferably a flat plate attached to an adjusting screw, the thread of which engages in a bracket extending upwardly from the lower clamping surface. In order to facilitate introduction and removal of the parts to be vulcanized, this bracket can be

2

pivotedly mounted on the pot-like lower part of the apparatus so that the upper clamping plate and bracket can be swung to the side. Conveniently, the upper clamping surface is mounted so that it can tilt to a limited extent in all directions and take up an inclined position so that a uniform transfer of pressure to the whole surface of contact of the parts to be vulcanized is ensured.

10 The drawing shows examples of construction of the vulcanizing apparatus according to the invention,

Fig. 1 being a side elevation,

Fig. 2 a front elevation, and

15 Fig. 3 a plan of a portable vulcanizing apparatus with pivoted bracket,

Fig. 4 is a longitudinal section through the movable lower clamping plate of this apparatus,

20 Figs. 5, 6 and 7 show the associated burner in side elevation and in front elevation and in plan,

Fig. 8 is a side elevation of another construction of apparatus with fixed bracket, and

Fig. 9 shows a burner for this apparatus.

25 The apparatus according to Figs. 1 to 3 consists of a press with two clamping surfaces 1, 2, which are circular in plan and used to press together the parts to be vulcanized. The lower clamping surface 1 consists of a plate 3 having a connector 4 which is removably fitted to the upper end of a pot-like container 5 which forms the base of the apparatus and receives a heating device. The container is provided on opposite sides with air inlet openings 6, and has at the front an opening 7 for the insertion of a burner which is supported on a floor 9 raised above the lower edge 8 of the apparatus, and the burner has a projection which fits in a hole 10 in the floor.

30 40 The container 5 has a rear extension 11, which constitutes a bearing for a pin 13 on the bracket 12, which is pivotally mounted in the extension 11. The head 14 of the bracket 12 supports the upper clamping surface 2 and is provided with an adjusting screw 15, to which is fixed the upper clamping surface 2 which is constituted by a flat plate 16. The connection between the screw 15 and the plate 16 is such that the plate has a certain freedom of movement and can be inclined to some extent in all directions. The upper clamping plate 2 is completely plane, while the center part of the lower clamping surface 1 is depressed somewhat below its rim (Fig. 4).

35 45 50 When vulcanizing a patch, for example on to a vehicle tire, the rim of the patch is subjected,

in consequence of this depression, to an increased pressure so that it runs out thin. The lower clamping surface 1 has a central die or engraving 17, which presses continuously on the vulcanized surface during use of the apparatus.

The screw 15 carries at its upper end a grip constituted by a cross pin 18. When the parts 1 and 2 are separated, the bracket 12 with the screw and the plate 16 attached to it can be swung to the side (Fig. 3), so that the lower clamping surface 1 is readily accessible for carefully laying on it the parts to be vulcanized.

The burner to be used in this case consists, as shown in Figs. 5-7, of a flat sheet 19 which carries a socket 20 of rectangular section for 15 reception of an elongated fuel cartridge 21 of resin, spirit or the like. A projection 22 on the under surface of the plate 19 fits into the centering hole 10 of the apparatus. The burner also comprises a lever 23 constituting an adjusting lever and pivoted at 24 to an upward projection 25 on the sheet 19, which passes through the socket 20 and which constitutes a spring engaging with teeth 26 of a member 27. On the member 27 adjoining the teeth 26 is a 20 scale corresponding with the external temperature. The end 28 of the adjusting lever is bent into hook form and constitutes a hand grip by means of which the burner can be gripped.

The fuel cartridge 21 rests loosely in the socket 20 and is supported at its lower end on the adjusting lever 23. According to the position of this lever the cartridge projects to a greater or lesser extent from the upper edge 29 of the socket 20. The projecting upper end of the cartridge is intended in use of the apparatus to provide heat appropriate for an operating temperature of about 140° C. If the apparatus is very cold, as in winter, the lever 23 is engaged with the top teeth so that the cartridge 21 projects to a maximum extent from the socket 20, while in summer, or when the apparatus is warm, as a result of previous use, the lever 23 is pressed down so that the cartridge projects only to a small extent. When the cartridge has burned down to the upper edge of the socket 20, it burns only with a moderate flame, which is sufficient to maintain the operating temperature necessary for vulcanization. In order to maintain the required size of flame, cut-away portions 30 are formed in the upper end of the socket 20 and serve to admit the necessary combustion air to the cartridge.

Fig. 8 shows a particularly small form of apparatus. In this case the lower clamping surface 31 is in one piece with the container 32. The container has on opposite sides air inlet openings 33 and a front opening 34 for the introduction of a burner 35, which is provided with a fuel cartridge 36 of resin, spirit or the like and has cut-away portions 37 in its end. The container 32 is constituted on the lower end of a rigid bracket 38 which also constitutes the base 39 of the apparatus and has a head 40 engaging the upper clamping surface, the screw

42 of the upper clamping surface 41 being movable in the head.

The invention is not limited to details of construction of the apparatus. Instead of a bracket with adjusting screw, other means can be used for pressing the upper clamping surface, for example the upper clamping surface can be pressed down by a spring or by means of a device similar to a beer bottle capper. The upper clamping surface can also be stationary and the lower clamping surface so constructed that it can be moved against the upper clamping surface either alone or together with the container.

Having now particularly described and ascertained the nature of our said invention and in what manner same is to be performed, we declare that what we claim is:

1. For use with a vulcanizing press including a base member with a central depression, a burner including a sheet having a depending projection receivable in the depression, a vertically extending socket tube secured on said sheet and including diametrically opposed longitudinal slots, a spring arm pivoted for vertical movement at one of its ends on said sheet and extending through said slots, an upstanding bar on said sheet adjacent said socket tube, vertically spaced teeth on said bar for retaining said spring arm in vertically adjusted position, and an elongated fuel cartridge received in said tube socket and resting on said spring arm.

2. For use with a vulcanizing press having a base having a central depression, a burner including a flat plate, a vertically extending socket tube mounted on said plate, said tube having diametrically opposed longitudinal slots therein, a spring arm pivoted for vertical movement at one of its ends on said plate and extending through said slots, the portion of said arm between said slots comprising a base for said tube, and an elongated fuel cartridge received in said tube socket and resting on said spring arm.

3. The combination of claim 2, wherein a vertical standard is mounted on said plate adjacent the free end of said arm, vertically spaced teeth on said standard for retaining said spring arm in adjusted positions.

WILHELM FRIEDRICH PETERS.
JOSEF RIESINGER.
